CLAIM

The ornamental design for a cover for dental chair, as shown and described.

DESCRIPTION

FIG. 1 is a side elevational view of the cover for dental chair showing our new design;

FIG. 2 is a front, side perspective view thereof;

FIG. 3 is a bottom view thereof;

FIG. 4 is a top view thereof;

FIG. 5 is a side view thereof;

FIG. 6 is a back side view, which is the opposing side view of FIG. 5;

FIG. 7 is a rear elevational view thereof; and,

FIG. 8 is a front, elevational view thereof.

The broken lines shown in the drawings are for illustrative purposes only and form no part of the claimed design.
